UNITED STATES PATENT OFFICE

105,102

DESIGN FOR A DISPLAY STAND OR SIMILAR ARTICLE

Mabel Harper, Long Island City, N. Y.

Application March 26, 1937, Serial No. 68,409

Term of patent 3½ years

To all whom it may concern:

Be it known that I, Mabel Harper, a citizen of the United States, residing in Long Island City, in the county of Queens and State of New York, have invented a new, original, and ornamental Design for a Display Stand or Similar Article, of which the following is a specification; reference being had to the accompanying drawing, forming part hereof.

In the drawing,

Fig. 1 represents a top plan view of a display stand, showing my new design,

Fig. 2 represents a front elevational view thereof,

Fig. 3 represents a side elevational view thereof, and

Fig. 4 represents a perspective view thereof.

I claim:

The ornamental design for a display stand or similar article as shown.

MABEL HARPER.
